UNITED STATES PATENT OFFICE

2,425,900

HEATED FOOD PACKAGE

Ray L. Steven, Los Angeles, Calif.

Application May 12, 1944, Serial No. 535,285

2 Claims. (Cl. 126—263)

1

This invention relates to article packaging and more especially to a package for food containers adapted to be heated prior to opening the food container.

An object of the invention is to provide a simple, practical and inexpensive food package of the character described.

Another object is to provide a food package having exothermic properties upon the addition of water to a chemical therein contained.

An additional object is to provide a food package adapted to be self-heating and adapted to receive standard food containers.

Other objects and advantages will appear and be brought out more fully in the following specification, reference being had to the accompanying drawing wherein:

Fig. 1 is an elevation view in central section of an embodiment of my invention.

Fig. 2 is a perspective view of the expandible wall shown in Fig. 1.

Fig. 3 is a view similar to Fig. 1 showing the lower portion of a modified form of the invention, and

Fig. 4 is a sectional view taken along the line 4—4 of Figure 3.

Referring more particularly to the drawing I show a food package comprising a shell 10 having spaced wall portions 11 adapted to retain therewithin a heat insulating material 12 such as asbestos or the equivalent, there being an annular opening 13 at the bottom for interfitting engagement with a bottom disc 14 of a construction similar to shell 10 and adapted to provide support for a supporting disc member 15. Disc 15 has an annular flange 16 and a space 17 provided with lateral openings or passages 18 as shown. A standard food container 19 which may comprise a metallic can or the like is adapted to be positioned on flange 16, and a substantially cylindrical expander 20 is positioned between shell 10 and container 19, and provided with a tongue and groove connection 21 to permit the wall portion thereof to expand. A space 22 is provided between shell 19 and expander 20 to provide room for expansion of the expander and within the expander is a cartridge or sleeve 23 composed of lime or other suitable chemical which, when water is added thereto, will generate heat which is conducted into can 19 but is prevented by the insulating properties of shell 10 and disc 14 from escaping.

A cover receptacle 24 is shown as having a flange portion 25 for the top of shell 10 and an annular flange 26 positioned above cartridge 23. A plurality of holes 27 are formed through receptacle 24 providing passages for the flow of water 28 which may be placed in receptacle 24 and conducted to and into the space containing the chemical 23. Cover 24 is provided with a neck

2

29 having a bore 30 which gives access to the top of can 19 for puncturing with a suitable tool in order to permit the escaping of air pressure developed within the can 19 when heated.

5 The operation of the invention as thus described should be clear. The package in dry condition is readily transportable and adapted to receive any standard can 19 suitable for the size of the package, and when it is desired to heat 10 the can a quantity of water is placed in receptacle 24 which passes through holes 27 into the chemical compartment 23, forming an effervescing solution which is exothermic, a portion of which passes through passages 18 into space 17, thus 15 heating the side portions and bottom of the can. This effervescing solution expands and thus expands expander 20 into space 22. Before or during the heating process the top of the can may be punctured by a sharp pointed tool inserted 20 through neck 29 to permit the escape of air pressure within the can.

The package may be used repeatedly by pressing the bottom disc 14 upwardly to remove the spent cartridge 23 which may be replaced with a fresh cartridge.

In Figs. 3 and 4 I show a modified form of the invention which comprises a shell 31 of any suitable thin walled material on a base 32 which latter supports a spacer block 33 for support of a can 34. Block 33 has a plurality of lateral passages 35 which lead between a central chamber 33a and an external space. Immediately within shell 31 is a corrugated wall 36 positioned in an expansion chamber or space and an exothermic cartridge 37 is positioned between wall 36 and can 34.

This package may be made exothermic in substantially the manner shown in Fig. 1 by suitably supplying water to cartridge 37 which becomes an effervescent solution, a portion of which passes through passages 35 into chamber 33a below can 34, the expansion of which solution may occur in the space formed by the envelope of corrugated wall 36 or by deforming 45 the same.

Having described my invention what I claim is:

50 1. A heated food package as described comprising an insulating shell having a cavity to receive a food container, a food container in said cavity, a chemical cartridge around said container, a wall forming an expansion chamber between said cartridge and said shell, and a cover and receptacle element for water having an aperture means to convey water to the chemical cartridge, said cover having a neck adapted to expose a portion of the top of the food container for puncturing.

55 2. A heated food package as described comprising an insulating shell having a cavity to

3

receive a food container, a food container in said cavity, a chemical cartridge around said container, a wall forming an expansion chamber between said cartridge and said shell, and a cover and receptacle element for water having means and receptacle element for water having means to convey water to the chemical cartridge, said shell having a removable bottom wall section to facilitate replacement of said chemical cartridge and food container.
